UNITED STATES PATENT OFFICE.

JAMES D. GIBBS, OF LOUISVILLE, KENTUCKY.

RAILWAY INTERLINE TICKET.

1,103,757.

Specification of Letters Patent. Patented July 14, 1914.

Application filed November 27, 1911. Serial No. 662,752.

To all whom it may concern:

Be it known that I, JAMES D. GIBBS, a citizen of the United States, residing at Louisville, in the county of Jefferson and State 5 of Kentucky, have invented new and useful Improvements in Railway-Tickets, of which the following is a specification.

My invention relates to that class of railway tickets variously designated as coupon, 10 through or interline tickets, the last named designation being preferred, and the objects of my improvements are to reduce the cost of providing tickets to cover the virtually innumerable routes and combinations of 15 railway lines in the United States and obviate as far as possible the necessity for voluminous ticket cases both at the railway and general offices and at ticket agencies.

A further object of my improvement is to 20 facilitate the agent's work of issuing interline tickets by placing on a single form all of the routes via common-way-points to a given destination or any designated station on a given terminal or final line of railway.

25 Heretofore it has been necessary for ticket agents to select from a large number of tickets the one applying via the route elected by passenger while in the use of my improved ticket a multiplicity of routes, perhaps all available routes via common way-points to a given destination, are embraced in one ticket thus obviating the necessity on the part of ticket agent of handling or inspecting a large number of different forms.

30 I am aware that multiple-route tickets are not new, but it is a fact that all which have been used or tried have proved impracticable for the reason that none of them have been so arranged as to effect a perfect record in 35 the offices of the issuing and participating railways, and for this reason no polyclute or multiple-route form of ticket has ever come into general use although the rapidly increasing growth of railway routes have 40 made imperative such reform in interline tickets.

The absolute necessity of effective recording or accounting features is obvious inasmuch as it is obligatory upon the part of the 45 issuing railway to properly apportion the revenue collected by the agent and remit to each participating carrier its due proportion according to the service rendered. It is equally important that each of the participating carriers have a correct and infallible record of the transaction in order to prop-

erly verify the accounting made by the issuing carrier and thus protect its own interests.

In the past, it has been ineffectually attempted to embrace in one ticket various divergent routes, while in my improved ticket only such routes as apply via common way-points are embraced in a single form, as will be seen by reference to the accompanying drawing, in which:—

Figure 1. is an interline ticket issued by the Louisville, Henderson & St. Louis Railway for a trip from any station on its line, via any one of twenty routes through St. Louis, Kansas City and Denver, to any destination situated on the Denver and Rio Grande R. R. Fig. 2. represents a form of ticket issued by the Louisville and Nashville R. R. reading from any station on any one of seven Atlanta Terminal lines, the elected line to be, in each case, indicated by punch marks. Fig. 3. is the agent's stub detached from ticket represented by Fig. 1, showing the preferred method of indicating the elected route, although it is entirely practicable to designate a route by punching out the proper route indicator *b*, *b*.

It will be noticed that the abbreviated names of railways representing the routes, *a*, in Fig. 1, are so grouped and alternated upon the coupons that when folded on the perforations and punched through all of the coupons upon both sides of any one of the lines of routing, *a*, as shown at *d* in Fig. 3, the ticket so punched will represent as distinct a route as if only one route were printed thereon, the route so designated being complete in itself and different from the route that would have been represented by the ticket had any other route been designated.

In practice, the ticket agent, after ascertaining from passenger the necessary information as to his destination and route, removes one of the tickets from his ticket case, and, after inserting the destination, folds all of the coupons and agent's stub on the perforated lines and with one impression of a hand or lever punch designates the route elected by passenger, after which the agent's stub is detached and retained by agent and the ticket delivered to passenger. In making his weekly or monthly report of sales the agent, by reference to his stub, enters upon the report the form number, *e*, of the ticket preceded by the proper route

indicator, *b*, as for instance H 325, the destination, consecutive number and rate at which the ticket was sold.

It will be seen that by reference to the chart of forms which is kept in all railway general offices, the rate-clerks having before them on agent's report the designated route indicator, are enabled to properly divide the through rate and credit to each participating carrier its due proportion of the revenue. Furthermore, it will be seen that the participating carriers could not accurately calculate and assure themselves of the correctness of the said apportionments unless each coupon bears exact information as to the starting point, destination and the geographical trend of the ticket throughout. It is the common practice to designate on the face of each coupon the destination, and stamp on back of each coupon the selling and starting point, and to complete the information required by all carriers I print on each coupon in geographical rotation the various junction points, *c*, via which the passenger is carried. The auditor and rate-clerks of all interested railways are thus enabled to properly check and protect their revenues, and this is not true of any other form of polyroute ticket heretofore devised for which reason none of them have ever been found practicable or come into general use.

While I prefer the letters of the alphabet as route indicating characters it is obvious that figures or any other distinctive characters may be used to obtain similar results without departing from the spirit of my invention. 35

Having thus described my invention, what I claim as new and desire to secure by Letters Patent is:— 40

1. A railway interline ticket having printed on a succession of coupons a plurality of railway names representing the routes of the ticket, each transverse line of routings being designated by a distinctive letter or character and having the junctions or common way-points printed in geographical rotation on each coupon as described. 50

2. A railway interline ticket having a multiplicity of routes printed in alignment across a series of coupons, each line of routing being designated by a distinctive letter or character, the said routes being arranged in a plurality of groups on each coupon, and having all of the common junction points via which the routes apply printed in geographical rotation on each coupon substantially as and for the purpose specified. 55
